S. BERKOVITZ.
SPOOL HOLDING APPARATUS FOR FACTORY MACHINES.
APPLICATION FILED MAR. 5, 1918.

1,303,015.

Patented May 6, 1919.

UNITED STATES PATENT OFFICE.

SAMUEL BERKOVITZ, OF NEW YORK, N. Y.

SPOOL-HOLDING APPARATUS FOR FACTORY-MACHINES.

1,303,015.

Specification of Letters Patent.

Patented May 6, 1919.

Application filed March 5, 1918. Serial No. 220,498.

To all whom it may concern:

Be it known that I, SAMUEL BERKOVITZ, a subject of the King of Roumania, and a resident of the city of New York, borough 5 of the Bronx, in the county of Bronx and State of New York, have invented a new and Improved Spool-Holding Apparatus for Factory-Machines, of which the following is a full, clear, and exact description.

10 Among the principal objects which the present invention has in view are: to prevent tampering with thread supplied to various mechanics in factories where thread is employed; to facilitate the keeping of stock 15 accounts, and particularly of the stock of thread used in factories employing the same, and to prevent the purloining of thread by mechanics using the same.

Drawings.

20 Figure 1 is a vertical section of an apparatus constructed and arranged in accordance with the present invention, the section being taken as on the line 1—1 in Fig. 2;

25 Fig. 2 is a horizontal section on an enlarged scale of said apparatus, the section being taken as on the line 2—2 in Fig. 1;

30 Fig. 3 is a horizontal section on an enlarged scale, of the apparatus, the section being taken as on the line 3—3 in Fig. 1;

35 Fig. 4 is a detail view showing in vertical section a portion of the mechanism of the locking mechanism with which the apparatus is provided, the section being taken as on the line 4—4 in Fig. 1;

40 Fig. 5 is a horizontal section on an enlarged scale, the section being taken as on the line 5—5 in Fig. 1;

45 Fig. 6 is a cross section on an enlarged scale of the mounting for the apparatus, the section being taken as on the line 6—6 in Fig. 1.

Description.

50 As seen in the drawings, the apparatus is designed to hold eight spools of thread, the spools in the drawings being indicated by broken lines and designated by the numeral 11. These spools are rotatively mounted on pins 12. The pins 12 are preferably provided with enlarged bases 13 mounted in an annular channel 14, which is inclosed and sealed. The pins 12 and bases 13 thereof are rotatively mounted in the base plate 15 and in the channel 14. While the base plate 55 15 and channel 14 are suspended beneath the

same are shown as rectangular in shape, it will be understood that there is no limitation as to the shape or extent of the area of said plate and channel.

60 The plate 15 is rigidly attached to a standard 16. The standard 16 is mounted in a pedestal 17, the base plate 18 whereof is held in service position by screws 19. At the upper end of the standard 16 is a canopy 20, from the edge whereof are pendent eyelets 21, through which is passed thread 22, which is carried from the spools 11. Intermediate the spools 11 and slidably mounted on the standard 16, is a cover 23. The cover 23 has a series of openings 24, the edge 25 whereof is curled to avoid abrading the thread 22 which is passed therethrough.

70 As seen best in Fig. 1 of the drawings, the pins 12 extend upward through the openings 24. The cover 23 is shaped in correspondence with the plate 15 and is provided with a central tube 26, as shown in said figure. The cover 23 with its tube 26, is freely slideable on the standard 16, except 75 when locked in its lowered position, in which position it prevents the lifting of the spools 11 from the pins 12.

80 Pendent from and permanently attached to the plate 15, is a lock case 27 in which is mounted a lock 28 of conventional design having a bolt 29 and a keyhole 30, as seen best in Fig. 1 of the drawings.

85 In the lowered position of the cover 23, a hook 31 with which the tube 26 is provided, 90 passes through an opening furnished in the top of the case 27 and extends below the bolt 29 of the lock 28 when the case is moved by the key outward therefrom. In this position, the bolt 29 holds the cover 23 rigid and 95 prevents the lift thereof.

100 The key which operates the lock 28 is usually carried by the superintendent of the factory or the keeper of the thread. When a mechanic requires thread, request is made to the keeper and the lock 28 is opened to permit the lifting of the cover 23. After the new thread has been placed on its particular pin 12, the cover 23 is lowered and the lock closed.

105 It will be understood that as a rule this apparatus is mounted on the work-table, bench or stand of a sewing machine and is intended for installation in factories where the mechanics use an assortment of threads. 110 In many instances, it has been the habit of the mechanics to appropriate a partially

filled spool, and this trifling loss to the concern becomes serious when multiplied by the number of mechanics employed. By using an apparatus constructed and arranged as above described and shown, this purloining is avoided.

5 The plate 15 and casing 27 are rigidly attached to the standard 16. The standard 16 is held in service on the pedestal 17 or similar structure by means of a set screw 32. The set screw 32 is operable for releasing the standard 16 and parts associated therewith, the object being to permit the mechanic using the apparatus to detach the 10 same from the machine or stand in order to take the former to the stockroom for supplies. In any event, it will be understood that the shop-keeper, superintendent, or other person in authority, is in possession of 15 the key by means of which the bolt 29 may be withdrawn from engagement with the hook 31.

Claims.

20 25 1. An apparatus as characterized comprising a supporting plate having a key-operated lock pendent therefrom; a standard permanently secured to said supporting plate and lock; a plurality of spool-holding 30 pins mounted on said supporting plate in

perpendicular relation thereto; a cover plate for said pins, said cover plate having a plurality of openings for guiding the thread from the spool on each of said pins; and a tubular support for said cover plate infolding said standard in sliding relation thereto, said support having a hook-like extension for engagement by said lock when said cover plate is in service relation to said pins and said supporting plate. 40

2. An apparatus as characterized comprising a supporting plate having a key-operated lock pendent therefrom; a standard permanently secured to said supporting plate and lock; a plurality of spool-holding 45 pins mounted on said supporting plate in perpendicular relation thereto; a cover plate for said pins, said cover plate having a plurality of openings for guiding the thread from the spool on each of said pins; a tubular support for said cover plate infolding said standard in sliding relation thereto, said support having a hook-like extension for engagement by said lock when said cover plate is in service relation to said pins and 50 said supporting plate; and a canopy, said canopy having guiding means for the thread delivered from the spools mounted on said pins.

SAMUEL BERKOVITZ.
